US0D1054582S

(12) **United States Design Patent** (10) **Patent No.:** **US D1,054,582 S**
(45) **Date of Patent:** **** Dec. 17, 2024**

(54) **ELECTROPORATION PROCESSING DEVICE**

(71) Applicant: **MaxCyte, Inc.**, Gaithersburg, MD (US)

(72) Inventors: **James William Luther**, Milan (IT); **Bertold Engler**, Altensteig (DE); **Andrea Besana**, Seveso (IT); **Thomas Alan Peach**, Milan (IT); **Frank Modica**, Silver Spring, MD (US); **Nicholas Chopas**, Germantown, MD (US)

(73) Assignee: **MaxCyte, Inc.**, Rockville, MD (US)

(**) Term: **15 Years**

(21) Appl. No.: **29/791,748**

(22) Filed: **Feb. 3, 2022**

Related U.S. Application Data

(63) Continuation of application No. 29/734,300, filed on May 11, 2020, now Pat. No. Des. 944,410.

(57) **CLAIM**

The ornamental design for an electroporation processing device, as shown and described.

DESCRIPTION

FIG. 1 is a front, top, right perspective view of an electroporation processing device, showing the new design; FIG. 2 is a rear, bottom, left perspective thereof;

FIG. 3 is a left view thereof;

FIG. 4 is a rear view thereof;

FIG. 5 is a front view thereof;

FIG. 6 is a top view thereof; and,

FIG. 7 is a bottom view thereof.

The broken lines of equal-length depict portions of the electroporation processing device that form no part of the claimed design.

1 Claim, 7 Drawing Sheets
